CLAIM

We claim the ornamental design for a ground glass tapered joint to mason jar adaptor, as shown and described.

DESCRIPTION

FIG. 1 is a top perspective view of a ground glass tapered joint to mason jar adaptor showing my new design.

FIG. 2 is a top plan view thereof.

FIG. 3 is a right side elevation view thereof, which is the same as the left side elevation view thereof.

FIG. 4 is a front elevation view thereof, which is the same as the rear elevation view thereof.

FIG. 5 is a bottom plan view thereof; and,

FIG. 6 is a top perspective view of my design in use.

The features shown in broken lines depict environmental structure only and form no part of the claimed design.

1 Claim, 2 Drawing Sheets
